2 Sheets-Sheet 2

UNITED STATES PATENT OFFICE.

STANLEY D. LIVINGSTON, OF NEW YORK, N. Y., ASSIGNOR TO EISEMANN MAGNETO CORPORATION, OF BROOKLYN, NEW YORK, A CORPORATION OF NEW YORK.

VACUUM-TUBE-CONTROL UNIT.

Application filed September 12, 1923. Serial No. 682,176.

My invention relates to radio receiving circuits and its object is to provide new and improved units for vacuum tube control, particularly detector units and amplifier units. Each unit is complete in itself, all parts being mounted on a single base, which is easily attached to a panel.

In a detector unit constructed in accordance with my invention, a single base carries a vacuum tube socket, a variable rheostat, a mounting for a grid leak, and a mounting for a grid condenser.

When my invention is applied to an amplifier unit, there is a base on which are mounted a vacuum-tube socket, a variable rheostat, and an audio-frequency (or radio-frequency) transformer.

In the preferred construction of my invention, the variable rheostat is mounted in a rotatable wheel surrounding the lamp socket. This produces an exceedingly compact arrangement. When the base is mounted on a panel, the periphery of the wheel projects through a slot in the panel for manipulation by the fingers. The rotatable rheostat has a fixed contact finger connected with one of the filament contacts of the lamp socket.

In each unit the parts are completely wired, so all the radio fan has to do it to attach the base to a panel, which may be done with a couple of screws. Furthermore, a detector unit and an audio-frequency amplifier unit may be mounted side by side on a panel and only a single wire is needed to connect them together.

Another advantage residing in my invention is a short direct connection from the grid contact of the lamp socket to the grid terminal of the other electrical element on the base. This prevents, or at least minimizes, loss of energy and feed-back action, which are liable to occur where the grid lead is too near the plate circuit.

The foregoing and other objects and advantages of my invention will become apparent from a detailed description of the accompanying drawings, which illustrate a detector unit and an audio-frequency amplifier unit in a form of construction which I have actually used and which I prefer at the present time. In these drawings, which show the parts in approximately full size,

Fig. 1 is a top plan view of a detector

unit constructed in accordance with my invention;

Fig. 2 is a bottom plan view of the unit shown in Fig. 1;

Fig. 3 is a longitudinal cross-section on line 3—3 of Fig. 1;

Fig. 4 is a detached bottom plan view showing the mounting of the rheostat in a wheel surrounding the lamp socket;

Fig. 5 is a rear end view of the unit shown in the preceding figures;

Fig. 6 is a side view of an audio-frequency unit embodying my invention;

Fig. 7 is a bottom plan view of the amplifier unit shown in Fig. 6;

Fig. 8 is a fragmentary front view showing the rheostat wheel projecting through a slot in a plate attached to a supporting panel;

Fig. 9 is a wiring diagram of the two units in bottom plan view; and

Fig. 10 is a section in line 10—10 of Fig. 8.

I will first describe the detector unit shown in Figs. 1—5.

All the parts are mounted on a base B, which may be formed of a single piece of sheet metal having side flanges 1 to increase its rigidity. An opening 2 is provided on the base near the front edge thereof, for a purpose to be presently explained. The flanges 1 terminate in a pair of perforated lugs 3 at the front edge of the base plate. In fact, these lugs may be said to constitute the front edge of the base plate B, as may be seen from Figs. 1 and 2. To secure the entire unit to a panel 4, it is only necessary to insert a pair of screws or bolts 5 through the panel and the holes in lugs 3, as illustrated in Figs. 1, 3 and 8. If necessary, the rear end of the base plate may be supported by a post or sleeve 6, through which passes a screw 7 into the bottom 8 of the box or cabinet containing the radio set.

On the base B is mounted a vacuum-tube socket (usually called a lamp socket), indicated as a whole by V. This socket comprises a cylindrical shell 9 and a set of four insulated contacts, which I have numbered 10, 11, 12 and 13. These insulated contacts, which are preferably resiliently mounted, extend across the opening 2 and so permit connections to be made at the underside of the base, as will subsequently be described. Contacts 10 and 11 are the two fila-

ment contacts, 12 is the grid contact, and 13 is the plate contact. As will be understood, these four contacts are arranged to engage the terminal posts of a vacuum tube when 5 the same is properly inserted into the shell 9. It is usual to provide a bayonet slot in the shell 9 for receiving a lug projecting laterally from the base of the lamp, so as to insure the correct positioning of the lamp in 10 the socket. The connections between the socket contacts and the lamp terminals are diagrammatically indicated in Fig. 9, where *f* represents the filament, *g* the grid, and *p* the plate of the lamp.

15 The form of lamp socket herein shown, particularly as relates to the mounting of the contacts, is in accordance with my invention as disclosed in my co-pending application Serial Number 608,214, filed December 20 21, 1922, and I do not, therefore, claim such construction in this case. In the broader aspect of my invention, the particular form of lamp socket is immaterial, for it is obvious that any practical type of socket may 25 be mounted on the base plate B. I need not, therefore, describe in detail the construction and mounting of the socket contacts 10, 11, 12 and 13, since reference may be had to my aforesaid co-pending application for such 30 details.

Around the base of lamp socket V is fixed a thin metal ring 14, which may conveniently be secured to the base plate by rivets 15, which in this instance also fasten the socket 35 contacts to the base. The ring 14 is provided at its upper edge with an outwardly extending flange 16 having a lug 17, as best shown in Fig. 1.

Surrounding the ring 14 is a rotatable 40 hand wheel indicated as a whole by W. The flange 16 of ring 14 holds the wheel in proper position on the base without interfering with its easy adjustment by the fingers of the operator. The wheel W is preferably 45 formed of a single piece of insulating material, such as bakelite, or any moldable composition suitable for that purpose. As may be seen from Figs. 3 and 4, the underside of the wheel is formed with an outer flange 18 and an inner flange 19, which provide a circular chamber or recess 20 adapted to receive a rheostat indicated as a whole by R.

In the drawings, the rheostat R is shown 55 in the form of a coil of wire wound on rod 21, but any other practical form of resistance unit may be used. A contact finger 22, preferably resilient is secured at one end to the filament contact 10 and is arranged to bear constantly against the rheostat R, whereby 60 one end of the rheostat is permanently connected to the filament contact 10. The other end of the rheostat is suitably grounded. In the present instance I have shown a contact member 23 secured to the rod 21 and connected to the grounded end of the rheostat. 65

The contact member 23, which may consist of a pair of spring fingers, as shown in Fig. 4, projects through a cutaway section 24 of the flange 19 of wheel W into contact with the ring 14. Since the ring 14 is connected 70 to the metal base B without being insulated therefrom, the contact member 23 always holds one end of the rheostat grounded to the base of the unit.

As seen in Fig. 1, the outer edge or periphery of the rheostate wheel W extends beyond the fastening lugs 3. In order, therefore, to accommodate this projecting portion of the wheel when the base is attached to a panel, as previously explained, the panel is provided with a slot of such dimensions as to receive the projecting edge of the wheel. Figs. 1 and 3 show the wheel W projecting through a slot 25 in the panel 4. The outer periphery of the wheel is preferably 85 knurled or roughened to permit easy turning of the wheel by the fingers. A suitable scale or index 26 may be marked on the outer rim of the wheel, as shown, for the purpose of indicating the amount or proportion 90 of resistance cut out.

The rotary movement of hand-wheel W in either direction is limited by suitable stops. In the embodiment shown in the drawings, the upper surface of wheel W is provided with a lug or stop 17' arranged to engage the lug 17 on the fixed ring 14 when the wheel is in full "on" and full "off" position. In Fig. 1, the stop 17' abuts against the left side of lug 17, and the operator 10 knows that the entire rheostat is cut out. When the wheel is turned until the stop 17' strikes the other edge of the lug 17, the full resistance is included in the circuit. Any other suitable means may be employed for 10 limiting the rotary movements of the rheostat wheel W.

On top of base B are mounted three supports, which in the present instance are shown in the form of sheet metal clips 27, 11 28 and 29. The clip 27 is secured to an insulated binding post 30 at the underside of the base plate and projects upwardly through an opening 31. Similarly, clip 28 is secured to a binding post 32, and clip 29 11 to binding post 33. Binding post 32 is suitably insulated from the metal base B, but binding post 33 is electrically connected to the base. Therefore, the clips or supports 27 and 28 are insulated, but support 29 is 12 grounded to the base.

As best shown in Fig. 5, clip 27 has a pair of holes 34 and 35, clip 28 has a hole 36, and clip 29 has a hole 37. The supports 27, 28 and 29 are so constructed and arranged 125 that a standard form or make of grid condenser is readily inserted in the openings 24 and 36, and a grid leak is similarly supported in the holes 35 and 37. Grid leaks and grid condensers usually come in the 130

shape of cartridges, which may easily be snapped into place between the spring clips, as stated. In Fig. 9, a grid condenser is diagrammatically indicated at K and a grid leak at L. The grounding of binding post 33 is diagrammatically indicated at x, and the grounding of one end of the rheostat R is similarly indicated at y.

From the underside of base plate B project two insulated binding posts 38 and 39. A metal strip 40 of good contacting material is at one end connected to filament contact 11 and at the other end to binding post 38. Similarly, a conducting strip 41 connects plate contact 18 with binding post 39. A conducting strip 42 leads directly from grid contact 12 to the insulated binding post 30, to which the supporting clip 27 is connected, as previously explained. In this way, one end of the grid condenser and one end of the grid leak are electrically connected to the grid contact 12 of the lamp socket.

It is advantageous in radio receiving sets to have the grid connection as direct as possible. If the grid lead is near a plate circuit, there is liable to be regeneration or feed-back action, which sometimes causes howling. In the construction of my invention, the grid connection 42 is short and direct, thereby obviating the objections and disadvantages just mentioned.

In order to prevent accidental contact of conductors 40, 41 and 42 with the metal base plate B, there is interposed an insulating sheet 43, which may be a piece of bakelite or other suitable insulating material.

In Figs. 6 and 7, I have shown an audio-frequency amplifier unit constructed in accordance with my invention. This amplifier unit differs from the detector unit in having an audio-frequency transformer T mounted on the base plate in lieu of the supports 27, 28 and 29. The lamp socket V' and rheostat wheel W' with their associated parts are the same as those described in connection with the detector unit, and I need not, therefore, repeat this detailed description. I need only describe the details of the mounting and connections of the transformer T. The outer casing of the transformer rests over an opening 44 in the base plate. An insulating disk 45 projects into the opening and at its outer edge 45' bears against the underside of the base plate, as may be seen in Fig. 6. A rod 46 passes through the transformer casing and through the disk 45. By tightening the nut 47 on the inner end of rod 46, the transformer casing and disk 45 are rigidly clamped against the opposite sides of the base plate, whereby the transformer is firmly held in position on the base of the unit.

I have not considered it necessary to show the interior construction of the trans-

former, because my present invention is not limited to any specific form or type of transformer. The transformer shown in Fig. 6 happens to be constructed in accordance with the invention disclosed in my co-pending application Serial Number 608,215, filed December 21, 1922, to which reference may be had for full structural details.

From the insulating disk 45 project four terminals or binding posts 48, 49, 50 and 51. Terminals 48 and 49 are connected to the primary winding of the transformer, as diagrammatically indicated on the right side of Fig. 9. Terminal 51 is connected by a conducting strip 42' to the grid terminal 12' of the lamp socket V'. Terminal 50 is connected to the insulated binding post 38' by a conductor 52.

I need not refer specifically to the other parts designated in Fig. 7 by reference numerals with prime marks ('), because those parts are the same as correspondingly numbered parts without prime marks in Fig. 2. The same applies to the two halves of Fig. 9, where corresponding parts have the same reference number; except that in the right half of the figure (the audio-frequency amplifier unit), I use prime marks with reference numerals for the sake of distinction.

It will be seen from Fig. 9, that when the two units are used in the same receiving set, the only electrical connection necessary between the two is a wire 53 leading from binding post 39 of the detector unit to binding post 48 of the amplifier unit.

In Fig. 8 I have a plate 54 secured over the slot 25 of panel 4. This plate, which may conveniently be stamped out of sheet metal, has a slot 55 in register with the panel slot 25 and adapted to receive the projecting edge of the rheostat wheel W. The slot 55 is preferably so shaped that it widens and recedes from the center point 56 toward the two ends. Fig. 8 shows the widened ends of slot 55 and Fig. 10 shows how the ends recede at 57 through the panel slot 25. The advantage of these widened and receding ends of slot 55 is to allow more finger space in manipulating the wheel by hand. At the same time, the narrowed center 56 of slot 55 forms an index point for the scale 26 on the rheostat wheel W. If desired, a mark 58 may be applied at the center of slot 55 nearest the scale of the rheostat wheel.

It is clear from the foregoing description that I have provided a vacuum-tube control unit of simple and compact construction, with all parts mounted on a single base and completely wired, requiring only a pair of screws to attach it to a panel. The only connections which the user need to make are the battery leads. As these connections are

well understood, I have not deemed it necessary to show or describe them. The connection between the detector unit and audio amplifier unit may be a simple wire or 5 it may be a connection with jacks.

It will be noticed that all binding posts and connections are at the underside of the base plate, where they are concealed from view and yet readily accessible. This 10 enhances the neat appearance of the unit as a whole.

Although I have shown and described certain specific constructions, I would have it understood that I have done so merely to 15 explain my invention and not by way of limitation. It is obvious that the broad features of my invention may be mechanically embodied in other constructions than herein set forth, without departing from 20 the scope of my invention as defined in the appended claims.

I claim as my invention:

1. A radio unit comprising a base, a vacuum-tube socket mounted on said base, 25 contacts for said socket, a rotatable wheel surrounding said socket, and having an outwardly projecting rim arranged to be touched by the fingers for easy adjustment of the wheel, a resistance element carried by 30 said wheel, and a radially extending contact finger engaging said resistance element, said contact finger being electrically connected with one of the filament contacts of said socket.

35 2. A radio unit comprising a base, a vacuum-tube socket mounted on said base, contacts for said socket, a rotatable wheel surrounding said socket, and having an outwardly projecting rim arranged to be 40 touched by the fingers for easy adjustment of the wheel, a resistance element carried by said wheel, a radially extending contact finger engaging said resistance element, said contact finger being electrically connected with one of the filament contacts of said 45 socket, and stops to limit the rotary movement of said wheel.

50 3. A radio unit comprising a base, a vacuum-tube socket mounted on said base, contacts for said socket, a rotatable wheel surrounding said socket and provided with a circular recess, said wheel having an outwardly projecting rim arranged to be touched by the fingers for easy adjustment 55 of the wheel, a resistance element mounted in said recess, and a contact finger engaging said resistance element, said contact finger being electrically connected with one of the filament contacts of said socket.

60 4. A radio unit comprising a base, a vacuum-tube socket mounted on said base, contacts for said socket, a rotatable wheel surrounding said socket and provided with a circular recess, said wheel having an outwardly 65 projecting rim arranged to be

touched by the fingers for easy adjustment of the wheel, a resistance element mounted in said recess, a contact finger engaging said resistance element, said contact finger being electrically connected with one of the 70 filament contacts of said socket, and stops to limit the rotary movement of said wheel.

5. In a radio unit, the combination with a vacuum-tube socket, of a rotatable rheostat surrounding said socket, and having an outwardly projecting annular rim arranged to be touched by the fingers for easy adjustment of the rheostat, and a contact finger for said rheostat.

6. In a radio unit, the combination with a vacuum-tube socket having the usual contacts, of a rotatable rheostat surrounding said socket and having a contact finger connected to one of the filament contacts of said socket, and an outwardly projecting annular 85 rim provided on said rheostat so that the same may be engaged by the fingers for easy adjustment of the rheostat.

7. In a radio unit, the combination with a supporting panel having a slot, of a base 90 secured to said panel, a rotatable wheel mounted on said base and so arranged as to project edgewise through said slot for manual adjustment, a resistance element carried by said wheel, and a fixed contact 95 finger for said resistance element.

8. In a radio unit, the combination with a supporting panel having a slot, of a base secured to said panel, a vacuum-tube socket mounted on said base, contacts for said 100 socket, a rotatable wheel surrounding said socket and so arranged on said base as to project edgewise through said slot for manual adjustment, a resistance element carried by said wheel, and a contact finger connected to one of the socket contacts and 105 engaging said resistance element.

9. A radio unit comprising a metallic base, a vacuum-tube socket mounted on said base and having the usual contacts, a rotatable 110 wheel surrounding said socket, a resistance element carried by said wheel and having one end grounded to said base, and a contact finger electrically connected to one of the filament contacts of said socket and arranged to engage said resistance element.

10. A vacuum-tube control unit comprising a sheet metal base provided at the front edge with lugs whereby said base is horizontally attached to a vertical supporting 120 panel, a vacuum-tube socket on said base, contacts for said socket, a rotatable wheel surrounding said socket and projecting edgewise forwardly beyond said lugs, a resistance element carried by said wheel, a 125 and a fixed contact finger for said resistance element, said finger being electrically connected to one of the filament contacts of said socket.

11. A radio unit comprising a base plate, 130

5 a vacuum-tube socket mounted on the upper side of said base plate, contacts for said socket, a rotatable wheel mounted on the upper side of said base plate and surrounding said socket, a circular recess in the underside of said wheel, a resistance element in said recess, four conducting strips rigidly connected to the socket contacts at the underside of said base plate, the strip which is 10 connected to one of the filament contacts being arranged to engage said resistance element, three binding posts at the underside of said base plate, and means for connecting the other three strips to said binding 15 posts.

12. In a radio unit, a base, a vacuum-tube socket mounted on said base, a fixed ring surrounding said socket and provided with a lug, a rotatable wheel surrounding said 20 ring, a resistance element carried by said wheel, a contact finger for said resistance element, and a stop on said wheel arranged to engage said lug.

13. A radio unit comprising a base, a 25 vacuum-tube socket mounted on said base, contacts for said socket, a rotatable wheel surrounding said socket, a resistance element carried by said wheel, a contact finger engaging said resistance element, said contact finger being electrically connected with one of the filament contacts of said socket, a grounded metal ring around said socket, and a conductor connected to one end of 30 said resistance element and permanently in contact with said grounded ring.

14. In a radio unit, a metal base, a vacuum-tube socket mounted on said base and provided with contacts, a metal ring fixed on said base and surrounding said socket, 40 said ring being grounded to said base, an insulating wheel mounted on said base and surrounding said ring, a flange on said ring for holding said wheel in position, a resistance element mounted on said wheel, a 45 conducting member connected to one end of said resistance element and slidably engaging said ring as the wheel is rotated, whereby said end of the resistance element is grounded to said metal base, and a contact finger connected to one of the filament contacts of said socket and slidably engaging 50 said rheostat.

15. In a radio unit, a metal base, a vacuum-tube socket mounted on said base and 55 provided with contacts, a metal ring fixed on said base and surrounding said socket, said ring being grounded to said base, an insulating wheel mounted on said base and surrounding said ring, a flange on said ring 60 for holding said wheel in position, a resistance element mounted on said wheel, a conducting member connected to one end of said resistance element and slidably engaging 65 said ring as the wheel is rotated, whereby said end of the resistance element is

grounded to said metal base, a contact finger connected to one of the filament contacts of said socket and slidably engaging said resistance element, a lug on said ring, and a stop on said wheel arranged to engage said lug for limiting the rotary movement of the wheel. 70

16. A radio unit comprising a base, a vacuum-tube socket mounted on said base, contacts for said socket, a rotatable wheel surrounding said socket, a resistance element carried by said wheel, a contact finger engaging said resistance element, said contact finger being electrically connected with one of the filament contacts of said socket, and 80 means for grounding one end of said resistance element to said base.

17. A radio unit comprising a base, a vacuum-tube socket mounted on said base, contacts for said socket, a rotatable wheel surrounding said socket and provided with a pair of spaced circular flanges which form a circular recess, a resistance element mounted in said recess, a contact finger electrically connected with one of the filament contacts 90 of said socket and arranged to engage said resistance element, a metallic member grounded to said base, and a conductor connected to one end of said resistance element and extending into sliding contact with said grounded member. 95

18. A radio unit comprising a base, a vacuum-tube socket mounted on said base, contacts for said socket, a rotatable wheel surrounding said socket and provided with a pair of spaced circular flanges which form a circular recess, one of said flanges having a cutaway section, a resistance element mounted in said recess, a contact finger electrically connected with one of the filament contacts 100 of said socket and arranged to engage said resistance element, a metal ring surrounding said socket and grounded to said base, and a conductor connected to one end of said resistance element and extending through said cutaway section into sliding contact with said grounded ring. 105

19. As a new article of manufacture for use in vacuum-tube control units, an insulating wheel adapted to fit around a vacuum-tube socket and provided with an open circular recess on one side thereof, said wheel being also provided with an outer rim arranged to be engaged by the fingers for easy rotation of the wheel, substantially as and for the purposes specified. 110

20. As a new article of manufacture for use in vacuum-tube control units, an insulating wheel adapted to fit around a vacuum-tube socket and provided with a circular recess on one side thereof, the other side of said wheel having a scale or index, substantially as and for the purposes specified. 115

21. As a new article of manufacture for 120

use in vacuum-tube control units, an insulating wheel adapted to fit around a vacuum-tube socket and provided with a circular recess on one side thereof, the other side of said wheel having a circular beveled portion provided with a scale or index, substantially as and for the purposes specified.

22. As a new article of manufacture for use in vacuum-tube control units, a flat wheel made of one piece of insulating material and constructed to fit rotatably around a vacuum tube socket, said wheel having a pair of concentric circular flanges arranged in a common plane at right angles

10 to the axis of the wheel, said flanges forming between them an annular chamber which is closed at one side and open at the other, substantially as and for the purposes specified.

15 23. As a new article of manufacture for use in vacuum-tube control units, an insulating wheel adapted to fit around a vacuum-tube socket and provided on one side with a pair of spaced flanges which form a circular recess, the outer flange being roughened and the inner flange having a section cut away, substantially as and for the purposes specified.

20 24. As a new article of manufacture for use in vacuum-tube control units, a flat wheel made of one piece of insulating material and constructed to fit rotatably around a vacuum tube socket, said wheel having a pair of concentric circular flanges arranged

25 in a common plane at right angles to the axis of the wheel, said flanges forming between them an annular chamber which is closed at one side and open at the other, and a resistance element mounted in said annular chamber and open to the air.

30 25. As a new article of manufacture for use in vacuum-tube control units, an insulating wheel adapted to fit around a vacuum-tube socket and provided with a circular recess on one side thereof, the other side

35 of said wheel having a circular beveled portion provided with a scale or index, and a resistance element mounted in said recess, substantially as and for the purposes specified.

40 26. As a new article of manufacture for use in radio-receiving sets, a plate adapted to be attached to a panel and having an elongated slot or opening which widens from the center toward the sides, the edge 50 of the plate extending rearwardly from the center of said opening toward the widened sides thereof, substantially as and for the purposes specified.

45 27. In a vacuum-tube control unit, a panel 55 having an elongated slot, a plate mounted on said panel and having an opening which registers with said slot, said plate being so constructed that the opening thereof widens from the center toward the sides, the edge 60 of the plate extending rearwardly from the center of said opening toward the widened sides thereof, an adjustable member projecting edgewise through said opening in the plate, said widened and receding portions of the opening providing increased finger space to permit easy manipulation of the member, and an electrical element controlled by said member.

50 28. In a vacuum-tube control unit, a panel 65 having an elongated slot, a plate mounted on said panel and having an opening which registers with said slot, said plate being so constructed that the opening thereof widens from the center toward the sides, the edge 70 of the plate extending rearwardly from the center of said opening toward the widened sides thereof, a wheel projecting edgewise through said opening in the plate, said widened and receding portions of the opening 75 providing increased finger space to permit easy manipulation of the wheel, and an electrical element controlled by said wheel.

80 STANLEY D. LIVINGSTON.
